UNITED STATES PATENT OFFICE

CARL HUGO JOHANSON, OF LOS ANGELES, CALIFORNIA, ASSIGNOR TO INTERNATIONAL GLOVE PROCESS COMPANY, LTD., A CORPORATION OF CALIFORNIA

GLOVE AND METHOD OF MAKING

Application filed October 14, 1930. Serial No. 488,571.

This invention relates to gloves and has for an object to provide a glove and method of making which will eliminate the glove thumb hole in the palm blank, and overcome the common provision of a thumb seam in the palm face of the glove.

It is an object to provide a method whereby the production capacity of an operator is greatly increased and whereby unskilled operators can be taught quickly to produce gloves by this new method in contrast to the time required heretofore to produce a skilled operator.

More particularly, it is an object to produce a glove structure consisting of practically only three pieces; namely: substantially duplicate palm and back members, each including a thumb element and a connector strip which may run from one side of the base of wrist of the glove to and between the several fingers and thumb and terminate at the opposite base of the wrist side of the glove; or the strip connector may start at the tip of the little finger and continue to and terminate at the tip of the fore-finger.

The invention consists in certain advancements in this art as set forth in the ensuing disclosure and having, with the above, additional objects and advantages; it being understood that modifications, variations, and adaptations may be resorted to.

Figure 1 is a plan showing matched superimposed back and palm blanks, prior to connection by a full border connecting tape.

Figure 2 is a perspective of a straight-edge connector tape, by means of which the relative edges of the back and palm blanks are connected.

Figure 3 is a perspective of a glove, showing a connector tape stitched in place and extending only from the tip of the fore-finger to the tip of the little finger.

Figure 4 is a perspective showing a full taped, boxed work glove.

Figure 5 is a plan of superposed blanks for a dress glove as of Figure 3.

It is understood that by the present method, any class of glove may be made and of any kind of material, it being a purpose to provide a method to attain a perfect fit of

glove in the various sizes as may be required.

According to the method, a back blank 2 and a palm blank 3 are cut out, each including required digits 4 and the thumb 5; these pieces being quite similar except that the fingers of the back blank are cut deeper as indicated at 6 so as to obtain a perfect fit at the roots of the fingers.

It will be understood that in making work gloves, the back blank 2 will be appreciably smaller in outline as compared to the palm blank 3 so that if a heavier palm material is used than is used in the back member (in order to insure longer wearing life) the seam 7 of the connector will be set back from the palm side to produce a box effect as is shown in Figure 4, the seam 8 being well up on the sides of the hand to prolong life.

The back and the palm members are adapted to be connected, at their relative edges, from the base of the wrist by the stitches 7 and 8 to the straight-edged, narrow connector tape 9 which may have beginning at the base of the wrist on one side and then extend entirely along the wrist sides and digit and thumb sides, and back to the opposite side of the wrist, as in Figure 4.

In Figure 3, the blanks 2 and 3 are shown as stitched at 10 directly together along the wrist sides, the thumb margins, and the outer margins of the fore-finger and of the little finger; the connector tape 9 commencing at a point *a* of the fore-finger and ending at a point *b* of the little finger, and joining the intermediate fingers.

It will be seen from the above that no thumb hole is needed in either palm or back blanks and that no stitch is presented at the ball of the thumb in the joining of the glove, thus enabling long life of the glove and providing a very economical method for production of gloves.

When the glove blanks are even, as in Figure 1, and full taped from side to side (as in Figure 4) the glove can be used reversibly on either hand, thus doubling its life.

If the glove is to be joined by a connector tape only between the fingers, Figure 3, then the palm blank 3 is made smaller than the back blank 2 as shown at zones 12, Figure 5,

to provide needed fullness at absence of the connector tape. The connector 9 is of particular value when used to connect the outer edges of the forefinger and the inner edges of the thumb of the glove, for in this way it makes a closely fitting glove, while permitting free movement of the forefinger and the thumb relatively to each other. It will be seen by referring to the drawing that the outer edges *c* of the forefinger portions are spaced apart from the tip of the forefinger portions to the thumb portions and that the inner edges *d* of the thumb portions are also spaced apart from the tip of the thumb portions to the forefinger portions. The connector 9 connects the said edges *c* of the forefinger portions and the said edges *d* of the thumb portions and this connector 9 extends from the tip of the forefinger portions to the tip of the thumb portions.

What is claimed is:

1. A glove having back and palm portions each having a forefinger portion and a thumb portion, the outer edges of the forefinger portions and the inner edges of the thumb portions being spaced apart respectively, and a connector having substantially parallel sides disposed at the said outer edges of the forefinger portions and the said inner edges of the thumb portions, the connector extending from the tip of the forefinger portions to the tip of the thumb portions and having its sides secured to the said outer edges of the forefinger portions and the said inner edges of the thumb portions to provide a closely fitting glove, while permitting free movement of the thumb and the forefinger relatively to each other.

2. A glove having back and palm portions each having a forefinger portion and a thumb portion, the outer edges of the forefinger portions being spaced apart from the tip of the forefinger portions to the thumb portions and the inner edges of the thumb portions being spaced apart from the tip of the thumb portions to the forefinger portions, and a connector having sides disposed at the said outer edges of the forefinger portions and the said inner edges of the thumb portions, the said connector extending from the tip of the forefinger portions to the tip of the thumb portions and having its sides secured to the outer edges of the forefinger portions and the inner edges of the thumb portions to provide a closely fitting glove, while permitting free movement of the thumb and the forefinger relatively to each other.

3. A glove having back and palm portions each having a forefinger portion and a thumb portion, the outer edges of the forefinger portions being spaced apart from a point adjacent the tip of the forefinger portions to the thumb portions and the inner edges of the thumb portions being spaced apart from a point adjacent the tip of the thumb portions

to the forefinger portions, and a connector having substantially parallel sides disposed at the said outer edges of the forefinger portions and the said inner edges of the thumb portions, the said connector extending from the tip of the forefinger portions to the tip of the thumb portions and having its sides secured to the outer edges of the forefinger portions and the inner edges of the thumb portions to provide a closely fitting glove, while permitting free movement of the thumb and the forefinger relatively to each other.
